(57) **CLAIM**

The ornamental design for a four-lug wheel rim, as shown and described.

DESCRIPTION

FIG. 1 is a front perspective view of a four-lug wheel rim showing the new design;

FIG. 2 is a back perspective view thereof;

FIG. 3 is a front elevational view thereof;

FIG. 4 is a back elevational view thereof

FIG. 5 is a right side elevational view thereof;

FIG. 6 is a left side elevational view thereof;

FIG. 7 is a top plan view thereof; and,

FIG. 8 is a bottom plan view thereof.

In the drawings, the broken lines depict environmental subject matter only and form no part of the claimed design.
